W. STRUTT.
BRUSH RAISING DEVICE.
APPLICATION FILED DEC. 18, 1914.

1,251,835.

Patented Jan. 1, 1918.

UNITED STATES PATENT OFFICE.

WILLIAM STRUTT, OF PITTSBURGH, PENNSYLVANIA, ASSIGNOR TO WESTINGHOUSE ELECTRIC AND MANUFACTURING COMPANY, A CORPORATION OF PENNSYLVANIA.

BRUSH-RAISING DEVICE.

1,251,835.

Specification of Letters Patent. Patented Jan. 1, 1918.

Application filed December 18, 1914. Serial No. 877,962.

To all whom it may concern:

Be it known that I, WILLIAM STRUTT, a citizen of the United States, and a resident of Pittsburgh, in the county of Allegheny and State of Pennsylvania, have invented a new and useful Improvement in Brush-Raising Devices, of which the following is a specification.

My invention relates to dynamo-electric machines and particularly to means for temporarily raising brushes out of engagement with the commutator cylinders thereof.

The object of my invention is to provide a simple and effective brush-raising device which shall be particularly useful when used in connection with rotary converters and similar synchronous machines that have main and commutating pole field windings and are adapted to be started from an alternating-current source.

In the accompanying drawings, Figure 1 is a view, in end elevation, of a part of a machine constructed in accordance with my invention. Fig. 2 is a view, partially in section and partially in side elevation, of the parts shown in Fig. 1, and Fig. 3 is a fragmentary view of a modification of the details of the brush-raising mechanism.

A field frame 1 serves to support an end-bell structure 2 that consists of an outer ring 3 in engagement with the field frame and a number of radially extending arms 4 which carry a rocker ring 5. The rocker ring 5 serves as a support for a plurality of regularly spaced, laterally and radially extending brackets 6, each of said brackets comprising a bar 7 that extends parallel to, and is spaced a suitable distance from, the commutator cylinder 8. Each of the bars 7 carries a plurality of brush holders 9 that are rigidly secured thereto. The brush holders severally comprise box-like structures 10 for the brushes 11 that bear upon, and are resiliently maintained in engagement with, the commutator cylinder 8 by means of springs 12.

The rocker ring 5 carries a pinion 13 that is fitted on a shaft 14 and is secured thereto by means of a nut 15 and a washer 16. The shaft 14 extends through and beyond the rocker ring 5 and supports a lever 17 that is retained on the shaft end by a suitable pin 18. A second ring 19 carries a rack 20 adapted to engage the pinion 13 and is provided, on its outer circumferential face, with

a reduced portion 21 to form a bearing surface for the inner face of the rocker ring 5. A plurality of bolts 22, provided with washers 23 and 24, serve to hold the ring 19 in proper relation to the rocker ring 5, so that the rack 20 will always be held in mesh with the pinion 13. Thus, the ring 19 may be rotated with respect to the rocker ring 5 by means of the lever 17. The ring 19 carries a plurality of regularly spaced lever arms 25 pivotally mounted thereon by means of tap bolts 26 and washers 27. The lever arms 25 are formed of a strong and durable fibrous insulating material that may be easily machined, thereby effectively insulating the brush-raising device from the frame of the machine. An arm 28 is provided, at one end, with a bifurcated portion 29 that embraces the free end of the lever arm 25 and is rigidly secured thereto by any suitable means, such as a bolt 31 and a nut 32. A second bifurcated portion 30 embraces a second lever arm 33 and is fastened thereto by a stud 34 and cotter pins 35 to provide a pivotal connection between the members. The lever arm 33 is rigidly secured, at its other end, to a rod 36 by means of a set screw 37. The rod 36 extends parallel to the brush holder supporting frame 7 and is rotatably mounted in brackets 38 carried thereby. The rod 36 carries a suitable cam member that is adapted to engage extensions 40 attached to the upper portions of the brushes 11. The cam member comprises a bar 39 that extends the length of the rod 36 and is supported parallel to and at a distance therefrom by the arms 41 that extend through holes in the rod. The arms 41 are provided with threaded portions and coacting nuts 42 so that the distance between the bar 39 and the rod 36 may be adjusted.

A modification of the brush-raising mechanism is shown in Fig. 3 wherein the rod 36 is provided with a plurality of eccentric cam members 43 each of which is adapted to engage a single brush extension.

In order to raise the brush out of engagement with the commutator cylinder, the operating lever 17 is moved in a clockwise direction to produce a counterclockwise rotative movement of the ring 19 and of the lever arms 25. The lever arms 25, in turn, cause movement of the lever arms 33 and the rods 36 which thus bring the cam members into engagement with the brush 11.

extensions 40, with the result that the brushes are moved upwardly and out of engagement with commutator cylinder 8. When it is desired to return the brushes 5 into engagement with the commutator cylinder, the operating lever is moved to the position shown in the drawings, whereupon the cam members will become disengaged from the brush extensions, and the springs 10 12 will return the brushes to their original positions.

The projections upon the brushes are so designed that they will always be slidably engaged with the cam members until the 15 brushes are worn down to such a degree that they are no longer serviceable and, since there is no rigid connection between the brushes and the lifting means, no manual adjustment of the device is required to compensate for wear on the brushes.

While I have shown my invention in a simple and preferred form, it is not so limited, but is capable of various modifications of its structural features and other arrangements and location of parts such as may come within the scope of the appended 25 claims.

I claim as my invention:

1. A brush-raising mechanism for dynamo-electric machines comprising a brush holder, a cam device one member of which is carried by the brush and the other member of which is rotatably mounted, and means for actuating said rotatably mounted 30 member to cause it to slidably engage said brush-carried member and raise the brush.

2. A brush-raising device for dynamo-electric machines comprising a projection carried by the brush, a rotatably mounted 40 cam member, and means for actuating said cam member to cause it to slidably engage said brush-carried projection.

3. A brush-raising device for dynamo-electric machines comprising a brush holder, 45 a projection carried by the brush, a cam member adapted to engage the projection, and means for actuating the cam member

to cause it to engage the projection and raise the brush, the said cam being adjustably mounted whereby the travel of the brush 50 may be varied.

4. In a dynamo-electric machine, the combination with a support, a brush holder carried thereby, a projection carried by the brush and a rod rotatably mounted upon the support, of an arm carried by the rod and adapted to slidably engage said projection upon the rotation of the rod and to raise the brush.

5. In a dynamo-electric machine, the combination with a support, a brush holder carried thereby, a projection carried by the brush and a rod rotatably mounted upon the support, of an arm carried by the rod for engaging said projection and raising the 65 brush, the said arm being adjustable with respect to the rod whereby the travel of the brush may be varied.

6. In a dynamo-electric machine, the combination with a support, a plurality of brush 70 holders carried thereby, projections carried by the respective brushes and a rod rotatably mounted upon the support, of an arm carried by the rod for engaging the said projections and simultaneously raising all 75 of the brushes.

7. In a dynamo-electric machine, the combination with a support, a plurality of brush holders carried thereby, projections carried by the respective brushes and a rod rotatably mounted upon the support, of a U-shaped 80 arm, the end portions of which are secured to the rod and the intermediate portion of which is adapted to engage the said projections and to simultaneously raise 85 all of the brushes.

In testimony whereof, I have hereunto subscribed my name this 12th day of Dec., 1914.

WILLIAM STRUTT.
